HARVEY F. MARANVILLE, OF AKRON, OHIO, ASSIGNOR TO THE PERFECTION SPRING COMPANY, OF CLEVELAND, OHIO, A CORPORATION OF OHIO.

LUBRICATING SYSTEM.

1,071,068.

Specification of Letters Patent.

Patented Aug. 26, 1913.

Application filed December 12, 1910. Serial No. 596,870.

To all whom it may concern:

Be it known that I, HARVEY F. MARANVILLE, a citizen of the United States, residing at Akron, in the county of Summit and State of Ohio, have invented a certain new and useful Improvement in Lubricating Systems, of which the following is a full, clear, and exact description, reference being had to the accompanying drawings.

10 This invention relates to lubricating systems, and more especially to a system or apparatus of this type which is particularly designed for convenient application to and embodiment with the crank cases of internal 15 combustion engines, the exemplification shown herein having certain features adapting it specially for application to the crank cases of automobile engines.

It is the object of this invention to provide a system or attachment of the character referred to, which will always secure a supply of clean, cool oil to the engine, which is extremely compact, is readily adaptable to various styles of engines and 25 various conditions of use, and which will secure extremely efficient lubrication of the engine parts while reducing to a negligible minimum the loss of oil through heating the crank case and the carbonization of the 30 oil.

A further object of the invention is to provide an attachment or system having the foregoing advantages and which shall embody, in a self-contained construction, a 35 receptacle for oil overflowing from the crank case, a housing for the pump which forces the oil from this receptacle into a filter, a sight-feed, a ventilator for the crank case and said receptacle, a filler supplying oil to the receptacle, and an interceptor, in the nature of an exhaust head, by which oil in suspension in the gases 40 issuing from the crank chamber will be collected and delivered to the oil receptacle.

45 In the drawings accompanying and forming a part of this application, Figure 1 represents a side elevation of an engine for an automobile having my invention applied thereto, the hood being shown in dotted lines; Fig. 2 represents an enlarged sectional view taken through the engine base or crank case and my attachment, and Fig. 3 an enlarged detail, in side elevation, of a portion of the apparatus shown in Fig. 2.

55 As is well known to those familiar with the art of motor-vehicle engines, it is practically impossible to so pack the pistons as to prevent some of the gases, produced by the ignition of the explosive charges in the cylinders, from passing beyond the pistons 60 and into the crank case. This results in so heating the crank case as to carbonize the oil therein, with the result that partly consumed oil is discharged in the form of more or less dense smoke while the oil remaining 65 in the crank case rapidly darkens in color, on account of the carbonizing effect produced by such heat. To overcome this defect, practically all engines are provided with one or more outlet ports in the crank 70 case, called "breathers", through which the heated gases may escape and through which cool air may be drawn in on the up-stroke of the pistons to cool the crank case. The use of such "breathers" is, however, liable 75 to the serious objection that dirt will be drawn into the crank case, not only accumulating on the parts of the machinery to which it has direct access, but being deposited in the oil in the form of sediment. 80 This result has caused some engine makers to abandon the use of such breather apertures. A further objection to the use of such breather apertures is that the escaping gases are laden with oil in a suspended condition, particularly in the case of engines employing the "splash" system of lubrication. To prevent, to some extent, the loss of such oil, spiral arresters have been placed 85 in some breather outlets, but these arresters are inefficient and are also liable to the serious objection that the dirt which is drawn in with the air flowing into the crank case 90 will be deposited on parts of the spiral arrester and be carried back into the crank 95 case along with the oil that may accumulate on such arrester or that may be poured into the same in filling the oil reservoir. By the construction described and illustrated herein, I am enabled to employ a breather in 100 connection with the engine crank case which will be free from all of the objections noted, keeping the crank case cool without the loss of oil, on the one hand, and the admission of dirt or other foreign substance, on the 105 other hand. Furthermore, the attachment whereby these results are secured also carries the pump for forcing the pure oil from a crank-casing overflow receptacle to a filtering and cooling tank, a ventilator which 110

is so arranged as to prevent any foreign material from entering the attachment or parts associated therewith, a filter for the aforesaid receptacle, an oil filler, and a sight indicator by which the level of oil in the receptacle may be conveniently ascertained.

Describing now by reference characters the various parts illustrated in the drawings, 1 denotes the hood of a motor vehicle, 10 said hood being shown in dotted lines in Fig. 1, and 2 the dash-board (shown in like manner). Within the hood and supported in the ordinary manner is the engine, shown herein as an engine of the four-cylinder 15 type, the cylinders being designated generally by the numeral 3. The cylinders are supported by an engine base or crank case comprising an upper section 4 and a lower section 5. In the embodiment of my invention 20 shown herein, the said sections are designed with particular reference to the accommodation of my lubricating system; but as will appear to those skilled in the art, the invention is equally applicable to the upper 25 sections of crank cases of standard construction, by merely substituting a special lower section for that ordinarily employed in the construction of such cases.

The upper section is shown as provided 30 with a short ledge 6, intermediate of the top and bottom thereof, and with the ordinary bottom ledge 7 extending substantially the length thereof but projecting outwardly near its middle portion, as shown at 8. This 35 middle outwardly projecting portion 8 has cast therewith a ventilator shaft section 9, said section being provided with a short, inwardly projecting flange 10, opposed to the flange 6. Near the upper end, this ventilator section is contracted in width, the contraction being conveniently formed by projecting inwardly a portion of the outer wall, as shown at 11, to form a substantially horizontal seat, with an upwardly projecting 40 flange 12. Above the flange 12 a strap 13 is provided, preferably cast with the ventilator section, said strap, seat and flange forming means for conveniently retaining in place a transparent gage 14, the upper end of which 45 is covered, as shown at 15.

16 denotes a hood for the upper end of the ventilator shaft, said hood being provided with a lug 17 projecting forwardly therefrom by means of which it is pivotally connected to a similar lug or projection carried by the upper end of the ventilator shaft section, as shown at 18. The hood 16 is similar in shape to a chimney cowl and is arranged to discharge rearwardly, the upper 50 end of the ventilator shaft and the hood 16 being so located as to be subjected to the draft through the hood produced by the fan 19, universally employed with automobile engines for the purpose of producing a circulation of air through the hood to assist in

cooling the engine parts. The lower end of the hood 16 is provided with a downwardly projecting flange 20, fitting the top of the shaft therebeneath. The rear end of the hood is provided with a spring catch 21 adapted to engage a corresponding projection 22 carried by the top of the shaft. A strainer 23, preferably of fine mesh wire gauze, extends across the top of the ventilator shaft, beneath the hood 16.

The lower section 5 is provided with a flange 24 by means of which it is bolted to the flange 7 carried by the upper section, as shown at 25. On its opposite side it is provided with a flange 26 having a central, outwardly projecting portion 27, corresponding to the flange 7 and the outwardly projected portion 8 thereof and being secured to the former flange and projection by means of bolts. Below the flanges 24 and 27, the bottom section is rounded, to accommodate the crank, and is provided with substantially vertical side walls 28 and 29 extending downwardly from the rounded portion.

30 denotes a bottom connecting the walls 28 and 29, the bottom extending the full length of the lower section. With the lower section, I employ a sediment chamber, substantially the same in construction as that shown in my application #585,819, filed October 7, 1910. In the present embodiment this sediment chamber is formed of cast or sheet metal having a rounded bottom, corresponding generally in contour to the rounded section of the lower crank case bottom and suitably secured thereto, as by means of rivets 31. The rounded bottom of this attachment is shown at 32 and is provided at its central portion with a downwardly projecting sediment chamber 33, preferably formed integral therewith and communicating with the crank case through a slot 34, said slot being formed in the lowest portion of this attachment. From the side of the slot toward which the crank 35 turns when "going ahead", as shown by the arrow in Fig. 2, there projects a sheet metal baffle or deflector 36, said deflector having its edge 37 deflected upwardly, whereby it extends a material distance above the opposite side of the slot 34, forming a discharge outlet therewith for sediment, which outlet has one side considerably higher than the other, to effectually intercept the sediment moved by the revolution of the cranks and deflect the same into the receptacle. The rounded bottom of the attachment corresponds to and forms in effect the bottom of the crank case and is provided with an overflow port 38 so located as to maintain in the crank case a level of oil of sufficient depth to permit the crank 35 to dip thereinto and sweep any sediment that may be present in the said attachment into the sediment chamber 33 provided by the walls 28 and 29 and bottom 30.

The crank 35 is provided with a "spoon" or dipper 35^a, which dips into the oil and insures lubrication by the "splash" system and at the same time facilitates the sweeping of the sediment into the chamber 33.

6 The bottom of the receptacle is provided with a suitable number of apertures adapted to register with apertures provided in the bottom 30 of the crank case.

10 A nipple 39 is threaded into the aperture provided in the bottom plate 30 and into the aperture provided in the bottom of the receptacle 33. For each such nipple, a removable plug 40 is provided, said plug being threaded into said nipple and projecting through the bottom plate 30. To insure the dipping of the cranks into the oil when the engine is tilted, as when ascending or descending a hill, and without the employment of an unnecessarily large quantity of oil, transverse partitions 41 are provided between the cranks.

15 42 denotes a housing section which is conveniently cast with the outwardly projecting flange 27 and the lower section 5 of the crank casing. This housing section is substantially co-extensive in width with the ventilator shaft 9 and its side walls 43 are cast with the adjacent curved and downwardly extending portions of the lower crank-case section, the wall 29 being provided with a port 44 communicating with the lower portion of this housing, the port being located below the level 45 of oil in the 20 receptacle provided in the bottom of the crank case section 5. The housing 42 is projected outwardly near the bottom, as shown at 46, and this outward projection is provided with an inwardly projecting flange 47, the upper surface whereof is on substantially the same level as the upper surface of the bottom plate 30. The outer edge of the bottom plate 30, corresponding to the housing 42, is thickened to provide a flange 48, 25 complementary to the flange 47, said flanges forming convenient means whereby a bottom plate 49 may be secured to the housing section.

30 The flange 47 provides a seat for a float 50, said float being provided with a stem 51 projecting upwardly through the ledge 11 and through an aperture provided in a projection 52 carried by the housing section. This stem is provided, within the sight gage 55 14, with an indicator 53. It will be apparent that the movement of the float will indicate the level of oil in the receptacle formed in the bottom of the crank case. The bottom plate 49 forms a support for the pump 50 gears 54 and 55, said gears being inclosed in an upwardly projecting housing 56 secured to the bottom plate. A pipe 57, the inner end of which communicates with the interior of the housing 56, leads to the filtering and 55 cooling tank 58, which may be of any suit-

able construction, such as shown in my application #569,569, filed June 29, 1910. From the filtering and cooling tank a pipe 59 leads into the crank case and is provided, in each compartment thereof, with a branch 60 discharging into such compartment. The pump gear 55 is shown as provided with a vertical shaft 61 extending through the flanges 8 and 27 and provided with a bevel gear 62 meshing with a similar gear 63 mounted on a shaft 64. This shaft may be driven in any convenient manner from the engine shaft 65, the shaft 64 being shown herein as the shaft which operates the igniter magneto 66. The gears 62 and 63 are 60 inclosed in a housing formed by a plate 67 secured to the flanges 6 and 10, the outwardly projected flange 8, and side plates 68 projecting inwardly from the ventilator shaft 9. This housing can be filled with 65 lubricant for the gears therein or said gears may be lubricated from the "splash system" employed in the crank case, through an aperture 68^a, which aperture will be provided in either event.

70 The lower crank case is provided with a breather aperture 69 which is located a short distance below the flange 27 and communicating with the upper portion of the housing 42. This breather aperture is larger than is usually provided, an efficient size for a 20 H. P. engine being some three inches long by one inch wide. A deflector 70 is secured to the upper wall of this outlet, as by means of a flange 71. The body of the deflector extends through the aperture and downwardly beyond the lower edge of said aperture, there being re-curved, to form the trough 72. This combined trough and deflector is of the full length of 75 the aperture and is provided with a discharge pipe 73 communicating with the bottom of the trough, preferably near the middle thereof, the ends of the trough being closed.

80 In operation, the gases passing around the pistons will escape through the aperture 69, will strike the downwardly directed deflector 70 and will have the oil particles contained therein separated by such deflector and collected in the trough 72, whence they are discharged, out of the path of the gases, into the oil receptacle provided in the housing 42. The gases pass, by the shortest route, to the ventilator shaft 9 and are discharged through the hood 16. The force of the draft created by the fan 19 past the rearwardly directed discharge end of the hood creates an aspirating effect upon the ventilator shaft and the crank case, with the result that air will not be drawn into the crank case on the upstroke of the pistons. Hence it follows that dirt and other foreign material cannot enter the oil compartment or the crank case and contaminate the oil 85 110 115 120 125 130

or injure the working parts of the machinery. The extremely large size of the breather outlet insures efficient ventilation for the crank case, and the latter is kept so cool in practice that the oil does not become carbonized. Further, there is practically no waste of oil in my system. As the oil is consumed in use, it can be conveniently replaced from time to time by merely folding back the hood 16 and using the ventilator shaft as a filler tube, the oil passing through the strainer 23. The pump forces the oil from the receptacle beneath the crank case into the filtering and cooling tank 58, whence it is forced by the same pump through the pipe 59 into the various compartments of the crank case. The quantity of oil in the oil receptacle can be conveniently ascertained, either by inspection of the sight gage 14 or of the gage 74, which is carried by the tank 58.

Having thus described my invention, what I claim is:

1. The combination, with an engine crank case having an aperture therein, of a ventilator shaft communicating with said aperture, and means, interposed in the path of the gases flowing from said aperture, for separating the oil from such gases.
2. The combination, with an engine crank case having an aperture therein, of a ventilator shaft communicating with and receiving the gases discharged through said aperture.
3. The combination, with a crank case having an aperture therein, of an oil receptacle below said aperture, a housing communicating with said aperture and provided with a discharge outlet, a separating device interposed between the said aperture and the said outlet, and means for discharging the oil collected by said device into the receptacle at a point outside the path of the gases discharged through said aperture.
4. The combination, with a crank case having an aperture in the wall thereof, of a housing inclosing said aperture and having a discharge outlet, an oil receptacle located below the aperture, a separating device in the path of travel of the gases discharged through said aperture and adapted to separate the oil therefrom, and a discharge pipe communicating with said device and discharging into said receptacle, the discharge end of said pipe being below the path of travel of the gases.
5. The combination, with a crank case having an aperture in the wall thereof, of an oil separating device interposed in the path of the gases flowing through said aperture, said device being secured to the upper wall of the aperture and extending downwardly therefrom and provided at its lower end with a trough, and a drain pipe connected with said trough.
6. In a motor vehicle, the combination of a hood, an engine in said hood, said engine being provided with a crank case having an aperture in the wall thereof, a fan in front of said engine and within said hood, a ventilator shaft communicating with said aperture and extending upwardly into the hood and having its discharge end directed rearwardly in the path of the draft created by the fan, and means interposed in the path of the gases discharged through said aperture for separating the oil therefrom. 70
7. In a motor vehicle, the combination of a hood, an engine in said hood, said engine being provided with a crank case having an aperture in the wall thereof, means for creating a draft through said hood, and a conduit communicating with said aperture and extending into the hood and having its discharge end in the path of the draft in said hood. 80
8. In a motor vehicle, the combination of a hood, an engine in said hood, said engine having a crank case provided with an aperture in the side wall thereof, a ventilator shaft communicating with said aperture and projecting upwardly therefrom and having its outlet end directed rearwardly, a fan in front of said engine arranged to circulate air through said hood and past the discharge outlet of the ventilator shaft, and a device arranged in the path of the gases flowing through the ventilator shaft and arranged to recover oil contained in said gases. 90
9. In a motor vehicle, the combination of a hood, an engine in said hood, said engine having a crank case provided with an aperture in the side wall thereof, a conduit communicating with said aperture and projecting therefrom and having its outlet end directed rearwardly, and a fan arranged to circulate air through said hood from front to rear and past the discharge outlet of the conduit. 100
10. In a motor vehicle, the combination of a hood, an engine in said hood, a fan in said hood in front of said engine, a crank case for said engine, said case having an aperture in the wall thereof, and a ventilator shaft receiving the gases flowing through said aperture, said ventilator shaft extending upwardly into the hood and having the discharge end directed away from said fan and in the path of the draft created by said fan. 110
11. In a motor vehicle, the combination of an engine, a crank case for said engine, said case having an aperture in the wall thereof, a ventilator shaft receiving the gases flowing through said aperture, and means for producing an aspirating effect upon the discharge outlet of said shaft. 115
12. The combination, with a crank case, of an overflow receptacle communicating with said case above the bottom thereof, a 130

- housing communicating with said receptacle, a filtering tank, a pump in said housing for forcing oil therefrom into said tank, a pipe extending from said tank to the crank case, 5 and an indicator mounted in said housing to show the level of oil therein and in the overflow receptacle. 70
13. The combination, with a crank case, of an overflow receptacle communicating 10 with said case above the bottom thereof, a housing communicating with said receptacle, a filtering tank, a pump in said housing for forcing oil therefrom into said tank, a pipe extending from said tank to the crank case, 15 the crank case being provided with an outlet aperture above the level of oil maintained in the bottom portion of the case, a ventilator shaft projecting from said housing, a separating device in said housing and interposed between said aperture and the ventilator shaft and arranged to discharge the oil deposited thereon into said housing, a float in said housing, a stem carried by said float and projecting through the ventilator, 20 and a sight gage carried by said shaft and into which said stem projects. 25
14. The combination, with a crank case, of a receptacle communicating with said case, a housing projecting from the crank 30 case and communicating with said receptacle, a tank, a pump in said housing for forcing oil therefrom into said tank, a pipe extending from said receptacle to the crank case, the crank case being provided with an aperture above the outlet to the receptacle, 35 a ventilator shaft projecting from said housing, and a separating device in said housing and interposed between said aperture and the ventilator shaft and arranged 40 to discharge the oil deposited thereon into said housing. 45
15. The combination, with a crank case having an oil discharge outlet, of a receptacle arranged to receive the oil flowing through 50 said outlet, an outwardly projecting housing carried by the crank case and communicating with the receptacle, a plate detachably connected to the bottom of the receptacle, a housing carried by said plate 55 and projecting upwardly therefrom, pump mechanism in the last-mentioned housing, a pipe communicating with the last-mentioned housing, a pump shaft extending through the first mentioned housing, and means for operating said shaft. 60
16. The combination, with a crank case having an outlet and having an aperture above such outlet, of a receptacle arranged to receive the oil flowing through said outlet and having a housing projecting laterally therefrom and inclosing said aperture, a ventilator shaft communicating with the housing and extending upwardly therefrom, such shaft having a laterally extending portion forming a seat, a gage mounted on said 65 seat, a float in the housing having a stem extending upwardly through said seat and into the gage, a pump in the housing, and means for supplying oil from said pump to the crank case. 70
17. The combination, with a crank case having an aperture in the wall thereof, of a ventilator shaft communicating with said aperture and having a rearwardly directed discharge outlet, said outlet being movably connected to the shaft, a strainer adjacent to the upper end of said shaft and extending thereacross, a receptacle for oil beneath said shaft, and means for supplying oil from said receptacle to the crank case. 75
18. The combination, with a crank case having an aperture in the wall thereof, of a ventilator shaft communicating with said aperture and having a discharge outlet projecting at an angle therefrom, and means 80 for separating the oil from the gases flowing through said aperture to the ventilator outlet. 85
19. The combination, with a crank case having an overflow opening above the bottom thereof and an aperture above said opening, of a receptacle for the oil overflowing through said opening, a housing communicating with said receptacle and said aperture and having a ventilator shaft 90 projecting upwardly therefrom, said shaft having a discharge outlet, a strainer in said shaft, and a pump connected with said housing and arranged to supply oil therefrom to the crank case. 95
20. The combination, with a crank case having an oil outlet and a gas exhaust aperture, of a receptacle below said outlet and having a ventilator shaft projecting therefrom, said shaft having a discharge elbow 100 pivotally connected thereto, and a strainer in the said ventilator shaft below said elbow. 105
21. The combination, with a crank case having an aperture in the wall thereof, of a discharge conduit for gases flowing through 110 said aperture and communicating therewith, and means whereby an aspirating effect is produced in proximity to the outlet end of said conduit. 115
22. The combination, with a crank case having an aperture in the wall thereof, of a conduit communicating with said aperture and adapted to receive the gases therefrom, means for creating an aspirating effect in 120 proximity to the discharge outlet of said conduit, and means interposed in the path of travel of the gases and adapted to separate particles of oil suspended therein and to discharge the oil thus separated out of the 125 path of movement of the gases. 130
23. A crank case comprising an upper and a lower section, the lower section having a bottom portion provided with an overflow opening adapted to maintain a

- level of oil therein and an aperture above said opening, a sediment receptacle communicating with the lower portion of such bottom, an oil receptacle carried by the 5 lower section, a housing also carried by the lower section and inclosing the said aperture and communicating with the receptacle, said housing having a discharge outlet in its upper portion, a ventilator shaft carried by 10 the upper section and communicating with the housing, a pump carried by said housing and adapted to supply oil therefrom to the crank case, and an oil separator in said housing and arranged to separate oil sus- 15 pended in the gases discharged through the aperture and to discharge the oil so separated into the housing at a point below the path of travel of the gases.
24. The combination, with an engine 20 crank case having a breather aperture, of means for producing an aspirating effect upon said aperture.

25. The combination, with an engine crank case having a breather aperture there- 25 in, of a housing inclosing said aperture, and means within said housing and in the path of gases escaping through said aperture for separating the oil from such gases.

26. The combination, with an engine crank case having a breather aperture there- 30 in, of a receptacle below said aperture, and an oil separating device in the path of the gases escaping through said aperture and arranged to discharge the oil separated from 35 said gases into the receptacle.

In testimony whereof, I hereunto affix my signature in the presence of two witnesses.

H. F. MARANVILLE.
